(57) **CLAIM**

We claim the ornamental design for a display screen or portion thereof with a graphical user interface, as shown and described.

DESCRIPTION

The FIGURE is a front view of a display screen or portion thereof with a graphical user interface showing our new design.

The heavy broken lines shown as part of the icon in the lower left forms part of the claimed design. The other, fine broken line showing of a display screen or portion thereof with a graphical user interface is included for the purpose of showing portions of the article which form no part of the claim.
